(57) **CLAIM**

The ornamental design for a saw handle grip, as shown and described.

DESCRIPTION

FIG. 1 is a perspective view of a saw handle grip showing my new design, with a hand saw shown in broken line form; FIG. 2 is a rear side view thereof;

FIG. 3 is a right side view thereof, which is a mirror image of the left side view;

FIG. 4 is a front view thereof;

FIG. 5 is a bottom view thereof; and,

FIG. 6 is a top view thereof.

The ornamental design which is claimed is shown in solid lines in the drawings. Any broken lines in the drawings are for illustrative purposes only and form no part of the claimed design.
